PREPARATION OF LITHOGRAPHIC PLATES

Charles F. King, Cincinnati, Ohio, assignor to
The Lithographic Technical Foundation, Inc.,
New York, N. Y., a corporation of Delaware

No Drawing. Application February 11, 1944,
Serial No. 522,625

7 Claims. (Cl. 101—149.2)

This invention relates to lithography and is directed particularly to improvements in the art of making positive reversal and deep-etch lithographic plates.

The conventional process of making a deep-etched lithographic plate consists in coating a grained metal plate with a film of dichromated colloid, exposing this film to a light image of the subject to be reproduced, developing to remove the unhardened film from the image areas, etching the metal surface slightly in the image areas, applying an ink or ink-receptive film to the etched image areas, then removing the light hardened colloid film or stencil from the non-image areas, and finally treating the non-image areas to render them receptive to moisture and non-receptive to ink.

In making a positive reversal lithographic plate these steps are exactly the same except that etching of the plate following the development is omitted.

When the light sensitive coating consists of dichromated glue development is accomplished by means of water and, following the development, the image areas are etched with a dilute acid solution in alcohol then rinsed with alcohol and dried. The plate is then ready to receive the ink or ink-receptive film.

When the light sensitive coating consists of dichromated gum arabic the image is developed by means of an acidulated solution of a salt, for instance, calcium chloride, magnesium chloride, zinc chloride, or a combination thereof, and is etched with a similar solution containing a more active acid or acid salt to remove some of the exposed metal. Following etching the plate is washed with an anhydrous alcohol and dried and, next, ink-receptive film is applied to the etched areas.

Lithographic plates of either of these types, while constituting an appreciable improvement over plates made by other methods, require considerable care in preparation, and occasionally they fail for lack of ability to retain a satisfactory ink-receptive image. The reasons for such failure are usually brought about through incomplete removal of hygroscopic salts from the etched image areas or incomplete drying of the etched image areas. Under these conditions the ink or ink-receptive film is inadequately bonded to the metal surface and during printing becomes detached as a result of the action of the moisture. The plate is then said to have become "blind." Unfortunately this trouble cannot be detected until the plate is on the press with the

result that a new plate has to be made and considerable time is lost.

In the case of plates coated with dichromated gum arabic it has been proposed recently to remove the residue of deep etching solution, and at the same time remove the resist by washing the plate in hot water, the purpose being to eliminate the use of the anhydrous alcoholic wash. While washing with water is no more deleterious to plate performance than washing with anhydrous alcohol still failures of the same type do occur because of the difficulty in removing the last invisible traces of moisture from the surfaces in the image areas. This difficulty is especially pronounced during periods of high atmospheric humidity. As a result neither washing with water nor washing with anhydrous alcohol provides plates which are uniformly satisfactory under all conditions.

This invention, briefly, is based upon the concept of treating the etched surfaces, after the etching solution has been removed, with an ink-receptive lacquer which is moisture absorbent whereby the plate is dehydrated or immunized against possible deleterious effects caused by traces of water at the etched surfaces. More specifically, the invention contemplates treatment with a lacquer containing a substantial portion of an anhydrous solvent which is capable of forming, with water, a minimum boiling point mixture, whereby the lacquer is endowed with the function, first, of exerting a drying effect upon the surface to which it is deposited, and then protecting that surface upon evaporation of the solvent-water mixture. This "dehydrating" lacquer enables consistently satisfactory results to be obtained under all weather conditions, whether the plates have been subjected to an alcoholic or cold water wash for removal of the deep-etching solution, or to a hot water wash for removal of both the etching solution and resist.

A representative composition having these properties consists essentially of a suitable film-forming resin and anhydrous isopropyl alcohol as the lacquer solvent. The isopropyl alcohol forms an azeotropic mixture with water, releasing vapors which, condensed, may contain as much as 9% water; otherwise expressed, the vapors given off are richer in water than the unvaporized solution. The azeotropic solution is negative, that is, it boils at a temperature lower than either of its two constituents. Therefore, the lacquer containing an azeotropic solvent effects dehydration of the surface upon which the lacquer is deposited and, upon evaporation, no trace of

moisture remains to interfere with the bond between the resin film and the metal surface. It also is to be observed that in conventional processes employing an alcoholic wash the alcohol is kept on the plate for some time and as it evaporates the plate is cooled. This cooling occurs to such a degree that the plate condenses moisture from the atmosphere after all of the alcohol has evaporated. In the present process the lacquer is applied only once; the moisture is removed by absorption and the evaporation which occurs does not cool the plate sufficiently to cause it subsequently to condense moisture. Moreover, the residue after evaporation is non-hygroscopic.

The dehydrating lacquers of the present invention contain a substantial portion of an anhydrous solvent in which the film forming resin is soluble and which itself is capable of forming an azeotropic solution with water, but it also has been determined that the solvent component of the lacquer system may contain appreciable percentages of various aromatic hydrocarbons, which sometimes are employed in lacquer formulation, without adversely affecting the dehydrating characteristics of the composition. In such instances ternary azeotropic mixtures are formed; in any event, a favorable rate of evaporation is displayed, the water present being evaporated along with the volatile organic solvents. Therefore, upon final drying of the resin film, the plate is freed from water and an ink-receptive base is provided even though the plate was moist when the lacquer was applied.

There are many resins which may be used as the film forming components of the lacquer systems including cellulose ethers, resins of the alkyd type, chlorinated rubbers and the like. While it is impossible to describe in detail all of the various film forming resin and solvent systems which may be used, three primary factors govern their selection. First, the resin should leave a film which is receptive to ink after the solvent has evaporated from it; second, the resin should be truly or colloidally soluble in anhydrous solvents capable of forming constant boiling mixtures with water; and any water present upon the plate when the lacquer is applied should leave the film by evaporation along with the solvent. Representative examples of compositions displaying these properties are as follows:

1		
Isopropyl alcohol	64	
Teglac 128—alcohol soluble maleic resin	16	
Xylool	20	
2		
Isopropyl alcohol	45	
Ethyl cellulose	5	
Solvent naphtha (coal tar naphtha)	50	
3		
Isopropyl alcohol	65	
Petrex SS. alcohol soluble alkyd	17½	
Xylool	17½	
4		
Pyridine	40	
Tornesite—chlorinated rubber	10	
Xylool	50	

While isopropyl alcohol and pyridine are given in the foregoing examples as representative anhydrous organic solvents various other solvent compositions displaying azeotropic properties have been described in the literature. These include ethyl alcohol, normal propyl, benzol plus isopropyl, toluol plus isopropyl, and the like. An azeotrope of ethyl alcohol contains only 5% of water

and as a practical matter evaporates somewhat too rapidly. An isopropyl alcohol azeotrope contains 9% of water and isopropyl alcohol therefore is more suitable as a dehydrant. Pyridine evaporates even more rapidly than ethyl alcohol and is also more expensive, and irritating to some people. On the whole, isopropyl alcohol or mixtures of isopropyl alcohol with other solvents are preferred. From the foregoing discussion of the principles of the invention, those skilled in the art readily will comprehend other materials which may be used to serve their function.

The lacquers of the present invention are employed in the usual way in the preparation of lithographic plates. The plates thus may be washed with anhydrous alcohol if the conventional practice is observed, to effect removal of the residual deep-etching solution, then blotted to substantial dryness, then lacquered. In the alternative, after deep-etching, the plates may be washed with hot water to cleanse them of etch solution and at the same time remove the bichromated colloid film in which event the plates also are blotted to substantial dryness and then lacquered. If it is desired to preserve the bichromated colloid film until after the application of the developing ink and still not use anhydrous alcohol then a suitable procedure is to wash the plates in cold water to remove the etching solution, dry the plates substantially, apply the lacquer and developing ink, and finally remove the resist.

Having described my invention, I claim:

1. The method of preparing a lithographic plate, which comprises the steps of removing deep-etching solution from the plate after it has been etched, drying the plate until it is substantially free of water and then effecting final removal of water from the etched areas of the plate by applying thereto a film forming lacquer containing a substantial portion of an anhydrous organic solvent which forms a negative azeotropic mixture with water residing on the plate, and effecting removal of the water from the lacquer by evaporation of the azeotropic mixture.

2. A method of dehydrating the etched area of a lithographic plate which has residual water thereon and establishing an ink-receptive lacquer film upon the plate, which method comprises applying to said etched area a lacquer consisting essentially of an anhydrous organic solvent which is capable of forming a negative azeotropic solution with water, and a film forming resin, forming a negative azeotropic solution between said lacquer and said residual water on the plate, and then dehydrating the plate and drying the lacquer by evaporating the azeotropic mixture of lacquer solvent and water absorbed from said plate.

3. A method of dehydrating the image areas of a lithographic plate which has residual water thereon, and establishing an ink-receptive lacquer film upon the plate, which method comprises applying to said etched areas a lacquer consisting essentially of a film forming resin and a combination of solvents capable of forming an azeotropic mixture with water having a minimum boiling point below that of any of said solvents and substantially below that of water, thereby absorbing the residual water at the etched areas, and then removing the water through liberation of vapors from said lacquer film which are richer in water than the film.

4. The method of preparing a lithographic plate which has residual water thereon after

etching, which method comprises drying the plate until it is substantially free of water, then effecting final removal of water from the etched areas of the plate by applying thereto a film-forming lacquer containing an anhydrous lacquer solvent which forms a negative azeotropic mixture with water residing on the plate and which also contains a coal tar solvent, and effecting removal of the water from the lacquer by evaporation of the azeotropic mixture.

5. The method of preparing a lithographic plate which has residual water thereon after etching, which method comprises drying the plate until it is substantially free of water, then effecting final removal of water from the etched areas of the plate by applying thereto a film-forming lacquer containing a substantial portion of anhydrous isopropyl alcohol which forms a negative azeotropic mixture with water residing on the plate, and effecting removal of the water from the lacquer by evaporation of the azeotropic mixture.

6. The method of preparing a lithographic plate which has residual water thereon after etch-

ing, which method comprises drying the plate until it is substantially free of water, then effecting final removal of water from the etched areas of the plate by applying thereto a film-forming cellulose ether lacquer containing a substantial portion of anhydrous isopropyl alcohol which forms a negative azeotropic mixture with water residing on the plate, and effecting removal of the lacquer from the water by evaporation of the azeotropic mixture.

10 7. The method of preparing a lithographic plate which has residual water thereon after etching, which method comprises drying the plate until it is substantially free of water, then effecting final removal of water from the etched areas of the plate by applying thereto a film-forming lacquer containing a substantial portion of an anhydrous organic alcohol which forms a negative azeotropic mixture with water residing on the plate and which also contains a coal tar solvent, and effecting removal of the water from the lacquer by evaporation of the azeotropic mixture.

CHARLES F. KING.
